WILLIAM GLASGOW, JR., AND JOHN G. WOOD, OF ST. LOUIS, MISSOURI.

Letters Patent No. 83,152, dated October 20, 1868.

IMPROVEMENT IN THE MANUFACTURE OF SHOT.

The Schedule referred to in these Letters Patent and making part of the same.

To all whom it may concern:

Be it known that we, WILLIAM GLASGOW, Jr., and JOHN G. WOOD, of St. Louis, in the county of St. Louis, and State of Missouri, have invented a new and useful Improvement in the Manufacture of Shot; and we do hereby declare that the following is a full, clear, and exact description thereof, which will enable others skilled in the art to make and use the same, reference being had to the accompanying drawings, forming part of this specification.

The object of this invention is to do away with the lofty towers now used in the manufacture of shot, which is accomplished by dropping the lead through a denser medium than air, such as mercury, glycerine, sirups, oils, &c., the temperature and density of which will be regulated according to the size of shot to be made.

The object of lofty towers is to give the shot time to form and cool during its descent through the air, and as the large shot requires much longer time to cool than the small, the tower for their manufacture must necessarily be proportionately higher, the largest shot requiring a height of about a hundred and fifty feet, while by our method it will only require a fall of about fifteen feet, the construction and operation of which will be understood from the following, reference being had to the accompanying drawing, which represents a sectional elevation of our apparatus.

The letter *a* represents a cylinder or tube of metal or other material, standing perpendicular, with a branch tube, *b*, extending from its base upward, at an angle of about thirty degrees.

c represents an annular charcoal-furnace, constructed so as to slide up or down on the outside of the tube *a*, for the purpose of heating the liquid or liquids contained therein at or near the surface, to a temperature as near as possible equal to that of the molten lead, the object being for the purpose of preventing the lead from being chilled too suddenly.

The tube is filled with oil, glycerine, or other suitable fluids, which are kept hot at the top by means of the adjustable charcoal-furnace *c*, thus allowing the lead, which is poured through a suitable sieve, *f*, into the tube, to be cooled gradually by first striking the hot

fluid near the furnace at the top, and sinking gradually into the cool fluid below.

The shot is caught in the ladle *d* as it falls down the tube, and is drawn out through the branch-tube *b* with its load of shot.

We do not limit ourselves to the use of a ladle for catching and drawing the shot out of the tube, but we propose using an endless band, with scoops or buckets attached, as clearly shown in red outline in the accompanying drawing. These scoops discharge themselves on the pan *e*, which leads into a suitable hopper.

We do not consider it necessary that we should here specify any particular means for adjusting the furnace, as it is obvious that various methods may be employed for the purpose, which will readily suggest themselves to the builder.

We prefer, however, in constructing the frame, to extend its central portion, as seen at *g*, and provide the same with thumb-screws, to work against the tube *a*.

Having described our invention,

We claim as new, and desire to secure by Letters Patent—

1. The method herein described of producing shot, consisting substantially in dropping the metal, in a molten state, through a column of glycerine, oil, or other similar fluid, instead of air.

2. The heating of said column at or near the top, so that the molten shot shall first impinge upon the heated portion of the medium, and be quickly cooled by its descent into the cooler portion of the same.

3. The employment of an adjustable heating-apparatus, so arranged and operating as to impart heat to any desired part of the cooling-column, substantially as and for the purpose set forth.

4. The construction of the cooling-reservoir with a lateral branch for the withdrawal of the shot, substantially as herein shown and described.

WILLIAM GLASGOW, JR.
JOHN G. WOOD.
